CLAIM

The ornamental design for a toy kitchen, as shown and described.

DESCRIPTION

FIG. 1 is a perspective view of a toy kitchen, showing our new design;

FIG. 2 is a front elevational view thereof, drawn on a slightly reduced scale;

FIG. 3 is a bottom plan view thereof;

FIG. 4 is a top plan view thereof;

FIG. 5 is a side elevational view thereof;

FIG. 6 is a side elevational view of the side opposite that shown in FIG. 5; and,

FIG. 7 is a rear elevational view thereof.

FIG. 1

FIG. 2

FIG. 3

FIG. 4

FIG. 7

FIG. 6
